Daniel B. SPATZ,
Inventor

Edgar H.
Attorney

UNITED STATES PATENT OFFICE.

DANIEL B. SPATZ, OF READING, PENNSYLVANIA.

DIRECTION INDICATOR.

Application filed December 4, 1922. Serial No. 604,702.

To all whom it may concern:

Be it known that I, DANIEL B. SPATZ, a citizen of the United States, residing at Reading, in the county of Berks and State 5 of Pennsylvania, have invented certain new and useful Improvements in Direction Indicators, of which the following is a specification.

This invention relates to improvements in 10 direction indicators and it is intended primarily for use on vehicles, and preferably such vehicles as are provided with a source of electrical energy.

The invention consists of a substantially 15 rectangular casing, capable of being supported at any convenient point on the vehicle, where it will be visible from both the front and the rear, and which is provided with a plurality of compartments having 20 transparencies at both the front and rear sides, each compartment containing an illuminating means, independently operable, and each provided with a direction indication, whereby the driver may disclose his 25 intention as to direction, to both the observer in the vehicle following, and to the traffic officer in front, simultaneously.

The invention is more fully described in 30 the following specification and clearly illustrated in the accompanying drawing, in which:

Figure 1 is a vertical central sectional view of my device. Figure 2 is a front elevational view of the edge of the casing with 35 the hood removed, and, Figure 3 shows a front view of the complete device.

The numeral 1 designates a casing of substantially rectangular form, provided with a hood member 2 adapted to form a closure 40 for the open side of the casing. The device may be supported on any suitable portion of the vehicle, as indicated at 3. The casing is formed with a series of partitions 4, horizontally arranged, and dividing the interior 45 into a plurality of compartments and each compartment is provided with a transparent front and rear wall 5 and on the inner faces of these transparencies, which are preferably colored so that they are transparent 50 only when a light is provided within the compartment, I provide a direction indication in the form of an arrow, or the word "Stop" as desired, the front and rear wall of each compartment being marked alike, so 55 that the indication marks on their inner surfaces cannot be read from the outside unless

the interior of the compartment is illuminated, and when so illuminated, the other indication marks in the other compartments will not be visible.

Between the hood member and the casing 60 1, I provide a plate 7, formed with its upper end 6 bent to lie on the top surface of the casing, while its lower end 6' is bent in the opposite direction, to lie against the under 65 side of the hood.

The flanges 6—6' serve to position the plate with relation to the casing, and to hold the lamps carried thereby in central position, 70 each in its respective compartment.

The casing is provided with a vertical wing 10 on each side, which wings are formed with screw holes 11 adapted to receive the screws 12 by which the hood is secured to the casing.

This plate carries a series of electric 75 lamps, 8, one lamp projecting therefrom into each of the compartments formed by the partitions and the casing wall. The lamps are provided with the usual 80 electrical connection to any suitable and convenient source of electric energy, such as a battery carried by the vehicle for general purposes, and the terminals of these connections will, as usual, be provided with any suitable means for actuating any 85 one of them independently of the others, which device may be located at any point within easy accessibility of the driver of the vehicle.

It will be noted that when the indicator is 90 operated, notice will be given to others in the rear, as to the direction about to be taken, and simultaneously the same notice will appear in the front, so that the traffic 95 officer will receive the signal at the same time as a following vehicle.

Having thus fully described my invention, what I claim and desire to secure by Letters Patent is:—

1. In a direction indicator for vehicles provided with a source of electrical energy, a rectangular casing, a removable vertical hood member adapted to form a closure for one end of the casing, a series of horizontal partitions formed within the casing, dividing the interior thereof into a plurality of compartments, a plate interposed between the hood member and the casing, said plate having a right-angled upper end resting on 100 the top of the casing and a right-angled lower end bearing against the under side of 105

the hood, a series of electric lamps, carried by said plate, one located normally in each of the compartments, and transparencies forming the front and rear sides of each compartment, whereon direction indications appear only when the lamp within the compartment is lighted.

2. In a device of the character described, a casing, a closure hood for the open end of 10 the casing, partitions in the casing dividing it into a plurality of compartments, a plate interposed between the hood and the casing,

said plate having its ends bent to engage the casing at one end and the hood at the other, electric lamps carried by the plate and projecting into the compartments, and transparencies in the front and rear of each compartment provided with direction indications on their inner faces which indications will be visible only when the lamp in the compartment is illuminated. 15 20

In testimony whereof I affix my signature.

DANIEL B. SPATZ.
